REFRIGERATING APPARATUS

Lawrence A. Philipp and Nicholas J. Bohn, Detroit, Mich., assignors to Nash-Kelvinator Corporation, Detroit, Mich., a corporation of Maryland

Application October 2, 1937; Serial No. 166,908

4 Claims. (Cl. 62—116)

This invention relates to an improvement in refrigerators and more particularly to the machine compartment of the refrigerator cabinet.

The invention consists of the refrigerator cabinet comprising a food storage compartment having an evaporator and a machine compartment located preferably beneath the food storage compartment. The machine compartment houses a compressor-condenser unit which is connected to the evaporator by suitable piping. This machine compartment has all of its walls lined or covered with a suitable insulating substance for the purpose of absorbing noises and sounds created therein during the operation of the compressor-condenser unit. The compartment is also provided in the wall thereof with intake and outlet openings or vents so that air may be circulated through the compartment by a fan mounted within the compartment and which air is drawn through the intake opening through the condenser and then expelled from the compartment.

The invention consists of certain novel features of construction and combination of parts which will be hereinafter described and pointed out in the claims.

In the accompanying drawing:

Fig. 1 is a view in front elevation of a refrigerator cabinet with portions of the front wall and door broken away showing the mounting of the parts within the cabinet.

Fig. 2 is a horizontal sectional view; and

Fig. 3 is a similar view illustrating a modification.

The invention consists of a heat insulated refrigerator cabinet 1 provided with a food storage compartment 3 in which is mounted a conventional type of evaporator or cooler 5. A heat insulated door 7 is provided for obtaining access to the food compartment. Located beneath the food compartment 3 is a machine compartment 10. The outer wall of the cabinet 1 is preferably constructed of metal and the inner surface of the compartment 10; that is, the top, bottom and side walls are lined with a suitable acoustic insulating material 12, of a character which will absorb noises, sounds and the like created in the machine compartment. This compartment has all of its walls tightly sealed by this insulating material excepting for an air inlet opening or vent 9 and an outlet opening or vent 11 formed in the rear wall thereof. It is to be understood that a door of suitable construction may be formed in a wall for obtaining access to the machine parts if desired.

Mounted within the machine compartment 10

is a refrigerant compressor 21 preferably arranged adjacent the intake opening 9. Associated with the compressor is a condenser 17 which may be of a finned coil construction. The condenser is mounted in the compartment 10 and interposed between the compressor and opening 9, and extending from the edges of the inlet vent 9 to the edges of the condenser 17 is a flexible sleeve 19 for directing the flow of air through the condenser 17. The flexible sleeve 19 may be of a fibrous or non-fibrous material such as canvas, rubber or the like.

Mounted within the compartment 10 and positioned in alignment with the outlet opening 11 is a motor 23. The motor 23 is provided with a shaft 27 having a fan 25 mounted thereon. This fan is preferably positioned within the opening 11. Mounted upon the shaft 27 is a pulley 29 over which travels a belt 28 which may be of V cross section. This belt passes over a pulley 31 carried by the compressor 21 whereby the compressor may be driven.

The compressed refrigerant is delivered by means of a pipe 35 from the compressor 21 to the condenser 17 and thence by pipe 37 to a high side float valve receiver 39 and then by means of a conduit or pipe 41 to the evaporator 5. The gaseous refrigerant is returned from the evaporator 5 by means of a pipe or conduit 33 to the compressor 21. The conduits 33 and 41 preferably extend through the wall of the storage compartment to the cooling element or evaporator 5.

Mounted or formed on the rear wall of the cabinet 1 is a vertical projection 13 which is adapted to engage the wall 15 of a room of a building for spacing the cabinet from the wall. The projection 13 is located between the openings 9 and 11, for separating the inflowing and outflowing air currents.

The heat generated in the machine compartment 10 by the compressor and condenser must be eliminated or removed from the compartment, and furthermore, the condenser must be cooled for converting the compressed refrigerant into a liquid refrigerant as it passes through the condenser. To accomplish this purpose the fan 25 is located in or adjacent to the outlet opening 11 and as the motor 23 is started for operating the fan and the compressor 21, the air will be drawn into the compartment 10 through the opening 9 and through the finned condenser 17 for extracting the heat therefrom. This air will then be drawn over the compressor for cooling the same and conducts any heated air emanating therefrom through the outlet opening 11. In this

manner the compartment is constantly receiving a fresh supply of air which is circulated therethrough for maintaining the compressor and motors in a cool condition as well as extracting 5 any heat that may emanate from the condenser and compressor. Also by drawing the air through the condenser much of the noise is eliminated and overcomes objectionable noise created by blowing the air through the condenser for extracting the heat therefrom.

10 Any noises or reverberations that may be created by the operating mechanism of the refrigerating system or due to the air circulating through the compartment 10 will be absorbed by 15 the sound insulating medium located around the walls of the compartment. In this manner provision has been made for absorbing any sounds created and for maintaining the operating parts of the refrigerating system in a cool condition, 20 thereby reducing, if not entirely eliminating, all sound or noises that would ordinarily emanate from these parts in the operation of a refrigerating system.

In the form shown in Fig. 3 a motorized compressor 43 is provided and the fan 25 is provided 25 with an independent motor 45. The operation of the system for cooling the condenser and machine compartment is similar to that previously described.

30 Aside from the specific embodiments of the invention herein shown and described, it will be apparent that numerous details of the construction may be altered or omitted without departing from the spirit and scope of the invention as 35 disclosed and claimed.

What we claim is:

1. In a refrigerator, the combination of an insulated cabinet comprising a food storage compartment and a machine compartment, said machine compartment having an air inlet opening 40 and an air outlet opening formed in a wall thereof, a compressor-condenser unit mounted in the machine compartment and having the condenser located adjacent the inlet opening, a flexible sleeve connected to the condenser and to the wall of the machine compartment around the air inlet opening so that the air entering the air inlet opening is directed through the condenser, and means for circulating air through the machine compartment for cooling the parts in the machine 45 compartment.

2. In a refrigerator, the combination of an insulated cabinet comprising a food storage compartment with a machine compartment separate

therefrom, said machine compartment having an air inlet opening and an air outlet opening formed in a wall thereof, a compressor-condenser unit mounted in the machine compartment and having the condenser located adjacent the inlet opening, 5 a flexible sleeve connected to the condenser and to the wall of the machine compartment around the air inlet opening so that the air entering the air inlet opening is directed through the condenser, means for circulating air through the machine compartment for cooling the parts in the machine compartment, and sound insulating material lining the wall of the machine compartment against sound transmission through the wall of the compartment and for the absorption of any 10 noise within the compartment.

3. In a refrigerator, the combination of an insulated cabinet comprising a food storage compartment with a machine compartment separate therefrom, said machine compartment having an air inlet opening and an air outlet opening formed in a wall thereof, a vertical projection on the outer wall of the cabinet and located between the inlet and outlet openings for separating the inflowing and outflowing air currents, a compressor-condenser unit mounted in the machine compartment and having the condenser located adjacent the inlet opening, a flexible sleeve connected to the condenser and to the wall of the machine compartment around the air inlet opening so that the air entering the air inlet opening is directed through the condenser, means for circulating air through the machine compartment for cooling the parts in the machine compartment, and sound insulating material lining the wall of the machine compartment against sound transmission through the wall of the compartment and for the absorption of any noise within the compartment.

4. In a refrigerator, the combination of a cabinet comprising a machine compartment and a storage compartment, said first named compartment having air inlet and outlet openings formed in a wall thereof for permitting the circulation of air through the machine compartment for cooling the same, a vertical projection on the outer wall of the cabinet located between said inlet and outlet openings and adapted to engage with a wall of a room and cooperate therewith to prevent the air leaving the outlet opening from mixing with air entering the inlet opening, and means in the machine compartment for circulating air therethrough for cooling the parts therein.
